UNITED STATES PATENT OFFICE.

EDWARD T. REDDING AND LEONARD W. CROSS, OF SWISSVALE, PENNSYLVANIA,
ASSIGNORS TO CONSOLIDATED EXPANDED METAL COMPANIES, A CORPORATION
OF PENNSYLVANIA.

METHOD OF MAKING EXPANDED METAL.

Application filed June 27, 1922. Serial No. 571,226.

To all whom it may concern:

Be it known that we, EDWARD T. REDDING, a citizen of the United States, and LEONARD W. CROSS, a citizen of Great Britain, both residing at Swissvale, in the county of Allegheny and State of Pennsylvania, have invented certain new and useful Improvements in Methods of Making Expanded Metal, of which the following is a specification.

This invention relates to a method of making expanded metal fabric. Metal fabric is ordinarily made according to two processes, one the "Golding", which is suitable for heavy stock and in which the diamonds are sheared from the blank by reciprocating die members, and the other the "deployed" method, suitable for lighter gauge stock such as used, for example, for metal lath and the other like meshes, some of which may be of material of heavier weight than ordinarily employed in lath. In this last process the blank is slit in a manner well understood and the metal is expanded by grasping the edges of the slit sheet and pulling them apart, so that the metal is deployed to produce the diamonds, the stretching of the strands being slight as compared with the stretching incident to the Golding process.

Our invention has, inter alia, to do primarily with improvements over the deploying method just described. Owing to the fact that the expanded sheet has a width many times greater than the width of the original blank, it will be seen that the practical limitations of the process are such that only one sheet of expanded metal can be produced at one time.

One of the primary objects of our invention is the provision of an improved process which is simple and effective and whereby we may, if desired, produce more than one sheet of expanded fabric at a time, preferably two sheets or multiples thereof. Thus the cost of production both as regards time and labor is greatly reduced.

We accomplish the foregoing, together with such other objects as may herinafter appear or are incident to our invention, by means of a process which we have diagrammatically illustrated in the accompanying drawings, wherein:

Fig. 1 is a plan view of a portion of a

blank suitable to carrying out our process; Fig. 2 is an end view of the blank; Fig. 3 is an illustration of the manner in which the deploying is carried out; Fig. 4 is a broken out side elevation of the sheets as they appear after the deploying operation; Fig. 5 is an end elevation of Fig. 4; Fig. 6 is an end elevation corresponding to Fig. 5 but illustrating the making of four sheets; Fig. 7 is a diagrammatic end elevation of a modified way of expanding the sheets; Fig. 8 is a longitudinal section through one form of machine suitable for carrying out the method; Fig. 9 is a section on the line 9—9 of Fig. 8; Fig. 10 is a section on the line 10—10 of Fig. 8; Fig. 11 is a side elevation of the machine on a reduced scale; Fig. 12 is an enlarged section on the line 12—12 of Fig. 11; and Fig. 13 is an enlarged plan view of the left hand end of Fig. 11.

In carrying out our process we take a blank A and pass the same through slitting rolls of ordinary construction and operation, with the exception that they are designed to slit the blank with groups of slits 7—two being shown in Fig. 1—such groups being spaced apart to leave an intermediate selvage 8 as well as the marginal selvages 9 and 10. It will be understood that the slits composing each group are arranged in staggered relation in the usual manner. After the blank has been slit instead of further upsetting the slit portions as is customary, we pass it through flattening rolls to take out the slight upsetting of the strands incident to the slitting operation, as we find this gives us a greatly improved product for the reason that a maximum measure of strength is retained at the bridges connecting the strands.

We deploy the metal in a direction transverse of the plane of the blank as indicated by the arrows in Fig. 2. In carrying out the operation by hand, the selvage 8 is supported and a length of the slit portions to either side thereof is pulled or pushed down in the manner indicated in full lines in Fig. 3. As there shown, the extreme end portions of the selvages 9 and 10 have been brought down to a point such that the diamonds *a* at such end of the blank have been fully deployed or expanded, such expansion being progressively less full or complete toward the right. Successive lengths of the slit portions are progressively brought down in this manner,

as indicated diagrammatically in the dotted lines in Fig. 3, until both portions have been fully deployed.

Where the blank is composed of such stock that the selvage will not accommodate itself to the slight foreshortening of the sheets which takes place under the expanding process, such selvage can be crimped slightly, preferably progressively, as indicated in exaggerated form at 11 in Fig. 3. The progressive displacement of the metal lends itself very well to the crimping operation as it will be apparent that it is only as diamonds are full deployed that crimping may be necessary. This crimping, it will be understood, will only be slight at most as the amount of foreshortening is relatively small.

It will be seen that in the expanding operation the blank assumes a general inverted V-shape, with the selvage 8 extending approximately in parallelism with the selvages 9 and 10, the expanded portions 12 and 13 which will eventually constitute the sheets 25 extending angularly between the selvages. It will thus be seen that the expansion is done in a direction generally transverse of the original plane of the stock which means that advantage is taken of the fact that by 30 expanding in this direction, instead of expanding in the same plane as the stock by pulling the selvages 9 and 10 apart, the whole operation can be carried out in a minimum of space. In this respect it will 35 be noted that it is unnecessary to move the selvages 9 and 10 apart at all and in point of fact such selvages may remain in their original positions as regards distance apart. The process, therefore, is one which also 40 lends itself readily to machine operation or machine methods.

After the stock has been expanded in the manner described, the selvage 8, which is preferably of double width, is slit, dividing 45 the expanded stock into two separate sheets and leaving edges of desired width for the two sheets.

In Fig. 6 we have illustrated the carrying out of our process in the production of four 50 sheets 14, 15, 16 and 17, the operation being the same in all respects with the exception that the blank is appropriately slit.

As an alternative, the operation may be carried out as indicated in Fig. 7. According 55 to the method there illustrated the expansion is divided and done partly above and partly below the plane of the blank. Thus where four sheets are to be formed, as in Fig. 6 the selvages 8^a and 8^b will be displaced upwardly and the selvages 9^a and 9^b and 9^c downwardly to progressively expand the slit portions therebetween, such progressive expansion being carried out as before described.

60 Referring now to the machine method as

illustrated in Figs. 8 to 13, the blank is first passed through the slitting rolls B—B which cut the groups of slits; and then it is passed through the flattening rolls C—C which take out the upsetting incident to the slitting, such flattening rolls also having, if desired, middle portions shaped to crimp the middle selvage, as indicated more particularly in Figs. 8 and 10. The slitting and the flattening rolls act to pull the blank forwardly and they, therefore, also "feed" the blank to the rest of the machine.

After leaving the slitting rolls, the middle selvage of the blank rides on to a supporting means such as a bar 19 and the portions of the blank to either side thereof pass under guides such as the plates 20—20 which terminate short of the middle selvage and are curved to carry the slit portions downwardly to the pairs of rolls 21—21. A pair of such rolls extend inwardly from each side from a suitable frame 22—22 in which they have bearings, the rolls terminating short of the middle selvage. The upper rolls engage the angularly extending portions of slit sheets at their inner edges, and the unexpanded portions pass between the rolls. The rolls, therefore, "feed" the blank and pull it through, and in conjunction with the guides expand those portions next to the intermediate selvage.

After leaving the rolls 21, the slit portions pass under the guides 22, which are shorter than the guides 20 and serve to direct the unexpanded portions through the rolls 23, which are shorter than the rolls 21. The slit portions adjacent the already expanded portions are thus expanded: additional guides 24, 25, etc., and pairs of rolls, 32, 33, etc., are provided in the number required for the particular width of sheets being made, it being understood that the rolls are progressively shorter.

The crimping of the edge selvage may be done by the rolls 40,—see Figs. 8 and 9; and the middle selvage may be split by the cutters 41—41, also seen in said figures. It will be understood that the rolls 40—40 and 41—41 serve, along with the other rolls, to pull the blank through the machine.

The method of driving the rolls will be clearly understood from inspection of Fig. 11. The pairs of rolls have meshing gears 42 and there are idlers 43, so that all may be driven from any suitable source of power. Cutters 41—41 may be driven from rolls 40—40 as by chains 44.

We claim:

1. The herein described process of making deployed expanded metal which comprises 125 slitting a blank, moving it along guide means engaging one selvage and thereby sustaining it, and expanding the metal transverse the plane of the blank by progressively and successively deploying from 130

said plane portions further and further from the edge supported as aforesaid.

2. The herein described process of making deployed expanded metal which consists in slitting a blank, in supporting the slit blank, in expanding the metal in a direction transverse the plane of the blank, progressively from one edge to the other, and crimping the edges of the blank, first at 10 the edge where the expansion begins, and at the other edge as expansion approaches it.

3. The herein described process of making a plurality of sheets of deployed metal fabric from a single blank which consists in 15 slitting the blank with a plurality of spaced groups of slits, in deploying the slit portions in a direction transverse the plane of the blank, and in separating the sheets.

4. The herein described process of making a plurality of sheets of deployed metal fabric from a single blank which consists in 20 slitting the blank with two groups of slits with selvage at the edge and intermediate the groups, and in deploying the slit portions in 25 a direction transverse the plane of the blank

so that in the resultant product the intermediate selvage will lie in a plane removed from the plane of the blank with the expanded portions extending angularly therefrom to the edge selvage in general V-shape, 30 and then in separating the sheets.

5. The herein described process of making a plurality of sheets of deployed metal fabric from a single blank which consists in 35 slitting the blank with two groups of slits with selvage at the edge and intermediate the groups, and in deploying the slit portions in a direction transverse the plane of the blank so that in the resultant product the intermediate selvage will lie in a plane removed from the plane of the blank with the expanded portions extending angularly therefrom to the edge selvage in general V-shape and then in separating the sheets by 40 splitting the intermediate selvage. 45

In testimony whereof, we have hereunto signed our names.

EDWARD T. REDDING.
LEONARD W. CROSS.
